UNITED STATES PATENT OFFICE

HARRY W. LAWRENCE, OF DENVER, COLORADO

ELECTRIC LIGHT FIXTURE

Application filed April 4, 1931. Serial No. 527,705.

This invention relates to an electric light fixture and has for its principal object the provision of a fixture which will constantly produce, in addition to illumination, a brilliant, scintillating, iridescent effect.

Another object of the invention is to provide means, in a fixture containing faceted jewels, for throwing light through the jewels at a multitude of constantly varying angles so as to cause the jewels to produce a continuous sparkling effect.

Other objects and advantages reside in the detail construction of the invention which is designed for simplicity, economy, and efficiency. These will become more apparent from the following description.

In the following detailed description of the invention reference is had to the accompanying drawing which forms a part hereof. Like numerals refer to like parts in all views of the drawing and throughout the description.

In the drawing:

Fig. 1 is a side elevation, partially in section, of an electric light fixture in which the invention is embodied.

Fig. 2 is a similar view illustrating an alternative design of the fixture.

Fig. 3 is a detail section illustrating the method of holding the lenses in place.

Fig. 4 is a horizontal section, taken on the line 4-4, Fig. 1.

The basic principle involved in this invention is to create a flashing, sparkling, scintillating effect in faceted jewels or lenses by constantly moving a light source positioned at the rear of the lenses. This principle is described more in detail in applicant's co-pending application Serial No. 497,473.

Fixtures embodying this principle can be made in various designs to obtain the desired effects. However, the outer casing of the fixture carrying the faceted lenses should always be positioned about a rotating element carrying electric lamps. Two methods for incorporating this construction in an electric light fixture are illustrated in the drawing.

In the form illustrated in Fig. 1, a bowl 10 is provided which is perforated to receive a plurality of faceted lenses 11. The lenses 11 are formed with peripheral flanges 12 that prevent them from passing through the 55 perforations in the bowl 10. They are preferably held in place by means of an inner bowl 13 carrying perforations corresponding to the perforations in the bowl 10. The inner bowl 13 clamps the flanges 12 of the 60 jewels against the inner face of the bowl 10 as shown in detail in Fig. 3.

A lamp supporting member 14 is arranged to rotate within the bowls in spaced relation thereto and carries a series of electric lamps 15. The lamp supporting member preferably comprises another smaller bowl or disk rotated in any desired manner. As illustrated, the lamp supporting member 14 is 65 carried upon bracket arms 16 projecting 70 from a motor shaft 17. The motor shaft is rotated by means of a relatively slow speed electric motor 18. The motor 18 may be carried in a motor bracket 19 which in turn is 75 suspended from the ceiling or other supporting structure by a standard 20. The bowl 10 is supported from the motor bracket 19 upon radially extending supporting arms 21. If desired, ornamental chains 22 may be 80 employed to create the impression that the outer bowl 10 is supported thereby.

An indirect lighting effect can be obtained by positioning a series of reflectors 23 upon the bowl bracket arms 21 so that they will 85 reflect light to the ceiling from a series of illuminating globes 24.

It will be noted that in use the light rays from the lamps 15 are projected through the lenses 11 at constantly varying angles. This 90 constant variation of the incident angle causes various facets upon the jewels 11 to illuminate so as to create an animated, scintillating effect in each jewel.

If desired, the lamp supporting member 14 95 can be provided with a projecting flange or deflector 25 to stop the rays of light from the lamps 15 so that no moving shadows will be thrown upon the ceiling.

In the form of fixture illustrated in Fig. 100

2, the driving motor, indicated at 26, is mounted in a canopy 27 directly at the ceiling. A motor shaft 28 extends downwardly through a sleeve 29 to the fixture proper. 5 A bowl 30 is supported directly from the sleeve 29 upon suitable bracket arms 31 and a lamp supporting rotor 32 is supported directly upon the lower extremity of the motor shaft 28. This form operates similarly to 10 the previously described form, that is, the rotor 32 rotates a series of lamp bulbs 33 in the rear of a series of faceted jewels 34.

It can be readily seen that the invention 15 will produce a striking ornamental effect, particularly desirable for ballrooms, banquet halls, theatre lobbies, etc., but it is not of course, limited to these particular uses.

It is desired to call particular attention to 20 the lamp supporting bowls or members 14 and 32. These serve a very important function in addition to carrying the lamps for they form a combined lamp support and reflector. The outer faces of these lamp supporting members act as reflecting surfaces 25 to throw rearwardly projected light rays forwardly through the lenses 11 and 34. In this way they not only greatly increase the amount of light thrown through the lenses but they increase the number of points from 30 which the light is projected and thereby increase the varying angles of the rays so that the total result is to greatly increase the scintillating, sparkling effect and the brilliancy thereof.

35 In the drawing, the light supporting members are shown directly connected to electric motors. It is, of course, understood that they may be connected by means of gears, belts, friction contacts and the like so as to 40 produce the desired speed of rotation of the lamp supporting members.

The electrical connections to the lamps or 45 motors have not been illustrated since the connecting of lamps is common knowledge and this can be done in any of the usual manners through collector lamps and brushes such as are always used when carrying current to a rotating lamp. One method of 50 carrying the current to the various lamp bulbs is illustrated in applicant's co-pending application, Serial No. 497,524.

55 While a specific form of the improvement has been described and illustrated herein, it is desired to be understood that the same may be varied, within the scope of the appended claims without departing from the spirit of the invention.

Having thus described the invention, what 60 is claimed and desired secured by Letters Patent is:—

1. An electric light fixture comprising: a 65 perforated outer bowl; faceted lenses carried in the perforations of said outer bowl; a lamp supporting bowl supported within said outer bowl and adapted to carry elec-

tric lamps; and means for rotating said lamp supporting bowl said latter bowl conforming in contour to said outer bowl and acting as a shield to prevent the light from said lamps from escaping through the open 70 side of said outer bowl.

2. An electric light fixture comprising: a rigid vertical supporting member; arms extending radially outward from said supporting member; a bowl supported at its open 75 side on said arms and extending downwardly therefrom; a rotating shaft axially positioned with reference to said supporting member and extending within said bowl; a second similarly contoured bowl carried by 80 said shaft within said first bowl and in parallel spaced relation therewith; a plurality of lamps projecting from the surface of said second bowl and adapted to shine through perforations in said first bowl; and means 85 for rotating said second bowl.

3. An electric light fixture comprising: a rigid vertical supporting member; arms extending radially outward from said supporting member; a bowl supported at its open 90 side on said arms and extending downwardly therefrom; a rotating shaft axially positioned with reference to said supporting member and extending within said bowl; a second similarly contoured bowl carried 95 by said shaft within said first bowl and in parallel spaced relation therewith; a plurality of lamps projecting from the surface of said second bowl and adapted to shine through perforations in said first bowl; 100 means for rotating said second bowl; and a peripheral flange formed around the open side of one of said bowls so as to shield the space between said bowls from projecting light.

In testimony whereof, I affix my signature.
HARRY W. LAWRENCE.
